UNITED STATES PATENT OFFICE.

PHILLIPS P. BOURNE, OF WINCHESTER, MASSACHUSETTS, ASSIGNOR TO WORTHINGTON PUMP AND MACHINERY CORPORATION, OF NEW YORK, N. Y., A CORPORATION OF VIRGINIA.

INTERNAL-COMBUSTION ENGINE.

1,415,864.

Specification of Letters Patent. Patented May 16, 1922.

Application filed June 14, 1921. Serial No. 477,392.

To all whom it may concern:

Be it known that I, PHILLIPS P. BOURNE, a citizen of the United States, residing at Winchester, county of Middlesex, and State of Massachusetts, have invented certain new and useful Improvements in Internal-Combustion Engines, fully described and represented in the following specification and the accompanying drawings, forming a part of the same.

It is the object of the present invention to provide simple and efficient means for recovering oil adhering to piston-rods of internal combustion engines, and particularly in engines of the cross-head type. In present constructions, the oil working up through the piston-rod stuffing-boxes is wiped off the piston-rod on the down-stroke and subsequently swept, by the scavenging air, into the power cylinder and burned, with consequent loss thereof and increased smokiness of the exhaust. According to the present invention, provision is made for collecting the oil thus wiped off the piston-rod in a chamber and forcing the same therefrom by scavenging air compressed on the outstroke of the piston, through connections from such oil-collecting chamber to a point insuring its return to the source of supply, or to other desired point, for reuse. The oil recovering means here disclosed, therefore, provides for efficient oiling of the piston-rod without waste of lubricant and with decreased smokiness of the exhaust.

For a full understanding of the invention, an engine embodying the same in its preferred form will now be described in detail in connection with the accompanying drawings, and the novel features thereof then be pointed out in the claims.

In the drawings—

Figure 1 is a vertical transverse section of an internal combustion engine, which may be of the Diesel type, showing the general arrangement of parts for carrying out the invention, and

Figure 2 is a sectional detail view of a preferred construction of piston-rod stuffing-box and oil drainage connections.

Referring now to the drawings, and particularly to Fig. 1, the engine shown is a two-cycle internal combustion engine, with inner crosshead guide and crank casing 10

and outer casing 11, which form a scavenging air-receiving chamber 12, into which air for scavenging purposes is drawn past automatic inlet valves 1 on the upstroke of the piston A. The piston rod 2 passes through a stuffing box 3 mounted above the crosshead guide as usual, such stuffing box being provided with the usual packing and also having an extension, preferably formed integral therewith, forming a hooded oil-collecting chamber 4, the piston-rod orifice 55 in the top of which is sufficiently large to prevent contact with the piston-rod and also permit free access to chamber 4 of scavenging air under compression on the down-stroke of the piston. The bottom of the chamber 4 is preferably coned, as shown, to facilitate drainage of oil therefrom through connections 5, such connections preferably leading to a point in the interior of the crosshead casing which will insure proper lubrication of the guide by oil forced through such connections, although it will be obvious that the oil may be led by such connections to any other point, such, for example, as the reservoir in the crank case, indicated generally by the numeral 6. In order to prevent backflow of oil in the connections 5, when the piston 2 is on the suction stroke, non-return valves of any well-known type, indicated generally at 8, 85 are provided in such connections, or the valves may be omitted and a small discharge opening from the stuffing box used in many cases.

From the foregoing it will be seen that as the oil adhering to the piston-rod 2 is wiped therefrom by the coned bottom of the chamber 4 on the downstroke of the piston and collects in the chamber 4, it is immediately forced therefrom through the connections 5 past the non-return valves 8, by the compression of the air drawn into the scavenging air receiving chamber 12 on the previous upstroke, such piston-compressed air having ready access to chamber 4 through 100 the enlarged piston-rod opening in the top thereof.

It will be understood that various changes and modifications made be made in the invention and still be within the scope of the 105 claims, and that the invention is not confined to use solely with internal combustion engines, but is applicable to any other

type of engine in which pressure is similarly available and applicable for oil recovery,

What is claimed is:

1. Oil recovering means for engines, comprising a piston-rod stuffing box having an open-ended oil-collecting chamber accessible to a piston-compressed medium, and an outlet from said chamber through which oil is delivered.
2. Oil recovering means for internal combustion engines, comprising a closed crank and crosshead chamber, a stuffing box above the crosshead, a hooded extension on said stuffing box forming an oil-collecting chamber open to the air compressed by the piston on its outward stroke, and an outlet connection from said chamber through which the oil is delivered.
3. Oil recovering means for internal combustion engines, comprising a closed crank and crosshead chamber, a stuffing box above the crosshead, a hooded extension on said stuffing box forming an oil-collecting chamber open to air compressed by the piston on its outward stroke, an outlet connection from said chamber through which the oil is delivered, and a non-return valve in said outlet.
4. Oil recovering means for internal combustion engines, comprising a closed crank

and crosshead chamber, a piston-rod stuffing box above the crosshead, an open-ended extension on said stuffing box forming an oil-collecting chamber accessible to air compressed by the piston on its outward stroke, 35 outlet connections from said chamber through which oil is delivered, and non-return valves in said connections.

5. Oil recovering means for internal combustion engines, comprising piston-rod stuffing box 3 and oil collecting chamber 4 open to the piston-compressed air, and one or more outlets 5.

6. Oil recovering means for internal combustion engines, comprising piston-rod stuffing box 3 and oil collecting chamber 4 open to piston-compressed air, one or more outlets 5 from said chamber to the crank chamber, and non-return valves 8 in said outlets.

7. Oil recovering means for internal combustion engines, comprising piston-rod stuffing box 3 and oil collecting chamber 4 open to piston-compressed air, one or more outlets 5 from said chamber for delivering lubricant to the crosshead guide, and non- 55 return valves 8 in said outlets.

In testimony whereof, I have hereunto set my hand.

PHILLIPS L. BOURNE
